UNITED STATES PATENT OFFICE

GIUSEPPE MATTIOLI, OF JERSEY CITY, NEW JERSEY

FIRE ESCAPE SAFETY DEVICE

Application filed June 3, 1930. Serial No. 459,027.

This invention relates to an improved device of a safety type usable in connection with a fire escape structure of the form employing a drop ladder and conventional counter-weight suspension means therefor.

In the form of fire escape under consideration, it is well known that a drop ladder is used in association with the lowermost balcony or landing.

10. As a general rule, pulleys are provided on the second balcony and the ladder is provided with cables trained over these pulleys and on the free ends of the cables are counter-weights.

15. This arrangement holds the ladder normally in an elevated state with respect to both the lower balcony and the one just above it, and in a position in readiness to be used in the case of an emergency.

20. With this arrangement, it frequently happens that the cables will break thus allowing the weight to drop and permitting the ladder to fall down and thus cause an uncontrollable accident.

25. With the foregoing objection in mind, I have evolved and produced an attachment for the lower balcony of such construction as to be normally effective, but to come automatically into play for catching and suspending the ladder in case of accident, caused by breaking of the cables or disconnecting of the weight.

30. My primary aim is to provide a safety appliance of this class which will not interfere with the operation of lowering the ladder in case of emergency, but which will come into play automatically in case of breakage of the cables or weights so as to prevent the ladder from accidentally falling down on pedestrians.

35. In carrying the inventive conception into practice, I have developed and perfected a simple, and expedient device in the nature of an attachment, which is directly actuated thru the medium of the counter weight, the

attachment being characterized by automatically projecting the hanger hooks which are normally out of the way of the rungs of the ladder, but which are brought into engagement with the rungs in case of accident.

50

In the drawings:—

Figure 1 is a side elevational view of a conventional fire escape structure equipped with the improved attachment.

Fig. 2 is an end view thereof, observing the structure shown in Fig. 1, in a direction from right to left.

Fig. 3 is a horizontal section showing, on an enlarged scale, the details of the safety attachment.

Fig. 4 is a top plan view of the pulley arrangement on the second balcony.

Figs. 5, 6 and 7, are detail perspective views.

In the drawings, in Figs. 1 and 2, the reference character 8 designates the first balcony or landing, and 9 represents the second balcony. The second balcony is provided with brackets for supporting a pair of pulleys 10 over which cables 11 are trained. The cables are attached at their free ends to the descending ladder 12. Incidentally the rungs of the ladder are represented by the numeral 13.

On the opposite ends of the cables are the counter-weights 14 which are shown as passing through guide straps 14^a provided for this purpose. The attachment is of a double or duplex type, and comprises attaching base 15 fastened on the bottom of the landing 8. On the outer edge, I provide a pair of duplicate brackets 16 which serve to maintain in place the safety catches or retainers 17.

Each retainer is the same in construction and a description of one will suffice for both. The retainer is formed from a single length of wire of appropriate gauge metal, which has a depending arm 18 terminating in a hook 19 for engaging the rungs 13. The upper end portion is formed with a crank portion 20 which constitutes a trip, and the intermediate portion 21 functions as a journal and is rock-

ably mounted in the bearing on the complementary bracket 16.

In practice, the hooked arms 18 hang down to the clearance position shown in Fig. 1 under normal circumstances. The trip ends or cranks 21 assume an upwardly inclined position overlying the adjacent edge portion of the base plate 15. In fact, the terminal of this part 20 underlies the adjacent end portion of the companion actuating arm 22. This arm is formed on one end with a counter-weight 23 and it is pivoted intermediate its ends on an upstanding bracket 24, provided on the plate.

The free end portion of the arm is disposed beneath the main counter-weight 14. The device is shown in normal position in Fig. 1 and the lower end portions of the counter-weights 14 rest lightly on the free end portions of the arms 22. The arms in turn rest in contact on the trip cranks 20. With this arrangement, when the cables 11 break the counter-weights 14 bearing down on the free end portions of the arms 22, will force the arms downwardly against the action of the weights 23, so as to trip the devices 17.

Obviously, this swings the hooks 19 outwardly in a path to engage beneath one of the rungs on the ladder 12, thus engaging the ladder and holding it temporarily to prevent it from falling down on the ground or on a passing pedestrian.

It is understood that the device is brought into operation, whether either one or both of the cables break or burn, or in the event that the weights themselves become disconnected from the cables or if the ladder 12 breaks loose.

The gist of the invention, it will be understood, is in the provision of a safety device on the lower landing 8, and embodying automatically tripped swingable retainers 17 so constructed as to be normally out of the way of the ladder to permit it to be employed for emergency conditions, but so located as to come into play for engaging an adjacent rung of the ladder in case of accidental breakage of the suspending means for the ladder.

The present embodiment of the invention has been disclosed in considerable detail merely for the purpose of exemplification, since in actual practice it attains the features of advantage enumerated as desirable in the statement of the invention and the above description.

It is to be understood that by describing in detail herein any particular form, structure, or arrangement, it is not intended to limit the invention beyond the terms of the several claims, or the requirements of the prior art.

Having thus described my invention, what I claim as new is:

1. In a structure for a fire escape structure including a counter-weight, in combination, a fire escape structure embodying stationary

vertically spaced landings, pulleys mounted on the upper landings, cables trained over said pulleys, weights attached to corresponding ends of said cables, a ladder attached to the opposite ends of the cables, said ladder occupying a suspended state between said landings, guide means on the lower landings through which the counter-weights pass, and safety ladder devices mounted on said lower landing in a position to be operated by either one or the other of said counter-weights.

2. A safety attachment for a fire escape landing comprising an attaching plate, swingably mounted and normally ineffective ladder retainers carried by said plate, and counter-weights-actuated means for rendering said device effective under predetermined accident position.

3. A fire escape safety attachment of the class described comprising an attaching plate, a bearing thereon, a depending arm provided with a ladder engaging hook, said arm being formed at its top with a journal mounted for rotation in said bearing, a projection formed on the upper end of said hooked arm, and swingably mounted means on said plate cooperating with said projection for bringing the hook into play in predetermined accident condition.

4. In a safety attachment of the class described, an attaching plate, an upstanding bearing carried thereby, an arm pivotally mounted intermediate its ends on said bearing, and provided at one end with a counter-weight and having its opposite end located for engagement with the counter-weight on the fire escape structure, and a ladder engaging device swingably mounted on said plate including means cooperable with the free end portion of said arm.

5. A safety attachment for a fire escape structure including counter-weights, an attaching plate provided with a pair of upstanding bearings, a pair of substantially horizontally disposed arms pivotally mounted intermediate their ends in said bearings, said arms being formed at their inner ends with weights, the outer end portions of the arms being adapted for location beneath the counter-weights of the fire escape construction, additional bearings on said plate located adjacent the edges of the plate, and a pair of ladder engaging devices cooperable with the free end portions of said arms, said devices comprising depending arms terminating in rung engaging hooks, journals mounted for rotation in the additional bearings, and crank portions having their terminal ends located beneath the free end portions of the weighted arms.

In testimony whereof I affix my signature.

GIUSEPPE MATTIOLI
